UNITED STATES PATENT OFFICE.

BENJAMIN RICHARDS, OF CANTON, MASSACHUSETTS, ASSIGNOR TO ALBENART COMPANY, OF CANTON, MASSACHUSETTS, A CORPORATION OF MASSACHUSETTS.

CLAMPING DEVICE.

1,126,867.

Specification of Letters Patent.

Patented Feb. 2, 1915.

Application filed August 28, 1913. Serial No. 787,059.

To all whom it may concern:

Be it known that I, BENJAMIN RICHARDS, a citizen of the United States, residing at Canton, in the county of Norfolk and State of Massachusetts, have invented new and useful Improvements in Clamping Devices, of which the following is a specification.

This invention relates to clamping devices of that type in which the work is held between a pair of relatively-movable jaws by pressure applied by means of a more or less independent mechanism embracing the jaws, and is intended to improve upon prior constructions of this general character in respect to facility and certainty of operation of the pressure-applying mechanism and in other ways hereinafter explained.

The features of construction and arrangement in which my invention resides are illustrated in one form in the accompanying drawings, in which:

Figure 1 is a side view, partly in elevation and partly in vertical section, of a clamping device embodying my improvements as preferably constructed; Fig. 2 is a transverse section on the line $x-x$ in Fig. 1; and Fig. 3 is in part a rear view and in part a transverse section on the line $y-y$ in Fig. 1.

The form of clamping device illustrated in the drawings, which is of a type suitable for use as a carpenter's bench vise, comprises a fixed jaw 2 adapted to be secured to the edge of a work bench 3, with the working face of the jaw extending vertically and having in front of it a parallel jaw 4 provided with a pair of horizontal rods 5 mounted to slide in suitable guides, so that the jaw 4 may be moved toward and away from the companion jaw 2. Cross plates or brackets 6 and 7 are carried by the jaws 2 and 4 respectively, and each of these brackets is apertured or slotted to receive a beam 8, which extends longitudinally beneath said jaws in the direction of their relative movement and is supported by the brackets as hereinafter described.

In the particular construction illustrated, the brackets 6 and 7 are suspended from the jaws by means of two pairs of hangers 9 and 10 which are pivoted at their upper ends to the rear and front faces of the jaws 2 and 4, respectively, and at their lower ends to the corresponding brackets on opposite sides of the beam 8, the two pairs of hangers being identical with respect to their

points of pivotal attachment so that the two brackets are adapted to swing laterally in like paths, carrying the beam with them. This arrangement is similar to that shown and described in U. S. Letters Patent No. 60 996,884, granted July 4, 1911, and is desirable in that it enables the point of application of the clamping pressure to be shifted laterally with respect to the work, but it is not essential so far as my present improvements are concerned.

Near its outer end the beam 8 is provided with a pressure-applying member consisting of an upwardly-extending arm 11, which is preferably bifurcated at its lower end to 70 straddle the beam 8 and is pivotally mounted on a transversely-extending pin 12 secured to said beam and passing through horizontal slots 13 formed in the opposite edges of the brackets 7, as shown in Fig. 1, the outer end 75 of the beam being thus suspended from the hangers 10. The arm 11 is operated by suitable means such as a hand lever 14 pivoted at one end within the bifurcated portion of said arm in position to bear upon the top of 30 the outer end of the beam 8, beyond the pin 12, this end of said lever being provided with a cam face so shaped that a downward movement of the lever from the position shown in Fig. 1 will force the upper end of 85 the arm 11 toward the jaw 2.

Behind the jaw 2 the beam 8 is provided with another upwardly-extending arm 15, the upper end of which is located directly opposite the upper end of the arm 11. In 90 the lower portion of said arm 15 is a slot 16 through which the beam 8 passes and which is so shaped as to cause the arm to cramp on the beam and lock itself thereto whenever the beam is sufficiently slanted with respect 95 to said arm, as, for example, by lifting the rear portion of the beam until the arm 15 is tilted backward thereon by the engagement of its upper end with the rear face of the jaw 2. This locking action may be made 100 more certain and effective by providing the arm 15 at the upper rear edge of its beam-receiving slot 16 with a few teeth 17 adapted to bite into the upper edge of the beam, the opposing point of resistance being located at 105 the lower front edge of said slot, which is somewhat in advance of the teeth 17. The lower portion of the arm 15 is located between rearwardly-extending flanges 18 with which the bracket 6 is provided and is sup- 110

ported on said bracket when unlocked from the beam, preferably by means of a lug or projection 19 resting on the top of a cross-piece 20 which unites the upper ends of the flanges 18 behind the arm 15, as shown in Figs. 1 and 3. The bracket 6 is also provided at its lower end with a cross-piece 21 located slightly above the bottom of the slot 16 when the arm 15 is in its unlocked position with respect to the beam, the function of this cross-piece 21 being hereinafter explained.

The jaw 2 preferably forms a part of a housing 22 adapted to be set into the work bench and having a rearwardly-extending portion 23 turned downward at its rear end and perforated as at 24 to receive the rods 5, whereby, in conjunction with perforations in the jaw 2 through which said rods pass, long guiding bearings for the rods are obtained. By making the perforations 24 oblong horizontally, as shown in Fig. 3, and providing for a slight amount of lateral play between the various parts of the device adjacent to the rear jaw 2, the jaws may be made capable of being placed against the tapering surfaces of a wedge-shaped piece of work and firmly clamped upon it.

So long as the beam 8 and the arms 11 and 15 occupy a position in which no clamping pressure is being exerted thereby, as in Fig. 1, the rear end of the beam is in its lowermost position and is supported by the cross-piece 21, the arm 15 being loosely supported by the cross-piece 20, and being tilted forward sufficiently to prevent engagement of the beam by the teeth 17 and the lower front edge of the slot 16. Said beam can therefore be slid freely in either direction through the slot 16, carrying with it the arm 11, jaw 4 and connected parts and thus providing for a quick adjustment of said jaw with respect to a piece of work placed between it and the jaw 2. After the jaws have been brought into engagement with the work the clamping pressure is applied by forcing the hand lever 14 downward, the first part of which movement results not only in pressing the upper end of the arm 11 against the jaw 4 but also in forcing the outer end of the beam 8 downward under the resistance opposed to said arm by the jaw 4 and the work behind it. This causes the beam to be tilted slightly on the pin 12 as an axis and lifted off the cross-piece 21, thereby tending to tilt the arm 15 forward, but this tilting tendency is resisted by the engagement of the upper end of said arm 15 with the rear face of the jaw 2, and hence said arm is caused to cramp on the beam and lock itself thereto as above described, simultaneously with a slight upward movement of the arm. The upper ends of the arms 11 and 15 are thus pressed toward each other and caused to

exert a pressure upon the work, which pressure may now be increased to any desired extent by forcing the lever 14 farther downward, the necessary relative movement between the arm 11 and beam 8 being provided for by the slots 13. On lifting said lever 14 the clamping pressure is relieved and the rear portion of the beam is permitted to drop until it rests on the cross-piece 21, whereupon the arm 15 unlocks itself from the beam and the parts are restored to their normal or relaxed condition, leaving the jaw 4 capable of free movement away from the work. To effect such movement it is merely necessary to pull backward on the lever 14, since the pin 12 connects the beam 8 to the arm 11 and also to the jaw 4 through the bracket 7.

As compared with the form of clamping device shown in the Letters Patent above mentioned, the present construction has the advantage that the rear portion of the beam is freed from its supporting bracket when the clamping pressure is applied, whereby the beam and its upwardly-extending arms are rendered independent of the brackets so far as their clamping effect is concerned and both brackets (and their hangers) are wholly relieved from strain. Hence a better application of the clamping pressure is secured, and the rear arm 15 is not liable to be unlocked from the beam in case the brackets are accidentally subjected to a blow or are jarred by operations performed on the work or on the bench to which the parts are attached. This arrangement also makes it possible to provide a cross-piece such as 21 for the beam to slide on independently of the arm 15, and thus the binding points on said arm are relieved from wear and all danger of accidental locking of said arm to the beam by an outward movement of the latter during quick adjustment is avoided. It is also an advantageous feature of the present construction that the beam is connected to the front arm 11 and the adjacent supporting bracket at the same point, since this obviates the necessity of providing for an upward movement of the outer end of the beam independently of the bracket, as in the prior construction previously referred to.

All these features may be employed in connection with various forms of pressure-applying devices and means for supporting the same, and their details of construction may be modified in various respects without departing from my invention.

I claim:

1. A clamping device comprising a beam provided with opposed pressure-applying members, one of which is adjustable lengthwise of the beam and has means for locking itself thereto when the beam is lifted, relatively movable jaws located between the

- pressure-applying members, means carried by one of the jaws for independently supporting the beam and its adjustable pressure-applying member, when unlocked, a bracket carried by the other jaw and having a pivotal support for the beam, and means for operating the pressure-applying members to clamp and unclamp the work.
2. A clamping device comprising a beam provided with opposed pressure-applying members, one of which is adjustable lengthwise of the beam and shaped to grip the latter when slanted thereon, relatively movable jaws located between the pressure-applying members, a bracket carried by one of the jaws and provided with means for independently supporting the beam and the adjustable pressure-applying member and permitting said parts to be moved into gripping engagement, a bracket carried by the other jaw and having a pivotal support for the beam, and means for operating the pressure-applying members to clamp and unclamp the work.
3. A clamping device comprising a beam provided with opposed pressure-applying members, one of which is adjustable lengthwise of the beam and has means for locking itself thereto when the beam is lifted, relatively movable jaws located between the pressure-applying members, a bracket carried by one of the jaws and provided with supports on which the beam and the adjustable pressure-applying member are respectively adapted to rest when unlocked, a bracket carried by the other jaw and connected to the beam by a transversely-extending pivot, one of said parts being slotted to permit relative longitudinal movement thereof, and means for operating the pressure-applying members to clamp and unclamp the work.
4. A clamping device comprising a beam provided with opposed pressure-applying members, one of which is adjustable lengthwise of the beam and has means for locking itself thereto when the beam is inclined, a bracket having means for independently supporting the beam and its adjustable pressure-applying member, when unlocked, another bracket having a pivotal support for the beam, relatively movable jaws located between the pressure-applying members, hangers for pivotally suspending said brackets from the corresponding jaws, and means for operating the pressure-applying members to clamp and unclamp the work.
5. A clamping device comprising a pair of jaws movable toward and away from each other, a bracket suspended from each
- jaw by means of pivotally-supported hangers, a beam passing through said brackets and provided with opposed pressure-applying members between which said jaws are located, one of said members being adjustable lengthwise of the beam and shaped to grip the latter when tilted backward thereon, cross bars carried by one of the brackets for independently supporting the adjustable pressure-applying member and the adjacent portion of the beam in proximity to the respective gripping edges of said members, a transversely-extending pivot pin connecting the beam and the other pressure-applying member and entering horizontal slots in the corresponding bracket, and a hand lever carried by the latter pressure-applying member and having a cam-shaped portion arranged to engage and press downward upon the beam at a distance behind said pivot pin.
6. A clamping device comprising a pair of jaws movable toward and away from each other and provided respectively with guide rods and with long bearings therefor, said bearings having provision for lateral play at a distance from the jaws to permit relative angular adjustment of the latter, a beam extending in the direction of relative movement of the jaws and provided with opposed pressure-applying members embracing the latter, and means for operating said members to clamp and unclamp the work.
7. A clamping device comprising a pair of jaws movable toward and away from each other and provided respectively with guide rods and with long bearings therefor, said bearings being laterally enlarged at a distance from the jaws to provide for relative angular adjustment of the latter, hangers pivotally supported by said jaws, brackets carried by the hangers, one for each jaw, a beam carried by the brackets and extending in the direction of relative movement of the jaws, opposed pressure-applying members carried by the beam and embracing the jaws, one of said members being adjustable lengthwise of the beam and having means for locking itself thereto, and means for operating the pressure-applying members to clamp and unclamp a piece of work placed between said jaws.
- In testimony whereof, I have hereunto subscribed my name this 25th day of August, 1913.

BENJAMIN RICHARDS.
